UNITED STATES PATENT OFFICE.

PATRICK RYAN, OF NEW YORK, N. Y., ASSIGNOR TO THE J. M. BRUNSWICK & BLAKE COMPANY, OF SAME PLACE.

BILLIARD-CUE CUTTER.

SPECIFICATION forming part of Letters Patent No. 254,703, dated March 7, 1882.

Application filed January 12, 1882. (Model.)

To all whom it may concern:

Be it known that I, PATRICK RYAN, of the city, county, and State of New York, have invented a new and Improved Billiard-Cue Cutter, of which the following is a full, clear, and exact description.

The object of my invention is to provide a device for cutting the ends of billiard-cues, having such construction that no difficulty will be experienced in making a true cut across the end of the cue.

The invention consists principally of a cue-receiving sleeve or shell, on the end of which is swiveled a stock that carries a hinged knife.

The invention further consists in providing the cue-receiving sleeve or shell with a clamping device for holding the cue, and also of the construction, combination, and arrangement of parts, as hereinafter described.

Reference is to be had to the accompanying drawings, forming part of this specification, in which similar letters of reference indicate corresponding parts in all the figures.

Figure 1 is a perspective view of my improved billiard-cue cutter. Fig. 2 is a longitudinal sectional elevation of the same; and Fig. 3 is a detailed plan view, partly in section, of the block for swiveling the shell and stock together.

A represents the shell or sleeve; B, the stock; and C, the knife-arm, which is hinged at *f* upon the stock, and which is provided with the cutting-blade *c*. The shell A is provided with the clamping-screw *d*, and is formed with the flange *b* at its forward end.

D is the block, which is secured upon the stock by the screws *i i*, for swiveling the shell and stock together, the block and stock being correspondingly recessed, as shown at *a a'*, and correspondingly channeled, as shown at *e e'*, to inclose and engage with the neck *b'* and flange *b* of the shell, as clearly shown in Fig. 2.

The stock is recessed at *g* in front of the recess *a'*, to form a continuous passage from the passage through the shell to the outer edge of the stock, so that there will be no obstruction to passing the end of the cue any desired distance through the shell under the knife.

The upward movement of the knife-arm C is

limited by the stop *h*, which in the drawings is shown as an ordinary headed screw; but any form of stop that reaches over the top of the knife-arm at a sufficient height may be used.

The face of the block D is made square, as clearly shown in the drawings, and forms an abutment and guide for the knife-arm to move in contact with, so that the knife will always move in a plane exactly at right angles to the shell A.

In use the end of the cue to be cut is to be passed through the shell the proper distance, and the cue clamped by the screw *d*. The stock and free end of the knife-arm are then to be grasped by one hand of the user and the shell is to be grasped by the other hand of the user. The knife-arm and stock are then to be firmly gripped by the hand, so that the knife will come forcibly in contact with the cue, and then the knife-arm and stock and the shell are to be worked reciprocally in opposite directions, or the shell held from turning in the hand, and the stock and knife-arm turned upon the sleeve and around the cue, so as to first form a shallow cut entirely around the end of the cue. This turning of the knife-arm and stock, or the reciprocal action of the knife-arm and stock, must be continued until the end of the cue is cut off.

It will be seen that as the cue and sleeve are securely clamped together and revolved, or held stationary as one part, the cue will be held from any longitudinal movement with respect to the knife, and that each successive cut around the circumference of the cue will always be directly in the line of the cut previously made, and as the knife is held and guided exactly at right angles to the shell and the cue, it follows that the cue must be cut off square and true; and it will be further understood that neither the knife or cue need any special guiding by the hands of the user, as is the case with the ordinary cutters, which have no clamping attachment for the cue.

The end of the screw *d* will be covered with a small piece of leather, rubber, or similar material, to protect the cue from being dented, scratched, or marred by the screw when it is screwed forcibly down upon the cue.

Having thus fully described my invention, what I claim as new, and desire to secure by Letters Patent, is—

1. A billiard-cue cutter made substantially as herein shown and described, and consisting of a cue-receiving sleeve or shell, on the end of which is swiveled a stock that carries a hinged knife for dressing the cue, as set forth.
2. The billiard-cue cutter made, substantially as herein shown and described, with a clamping attachment, whereby the cue may be clamped and held from longitudinal movement with respect to the blade during the cutting, substantially as set forth.
3. In a billiard-cue cutter, the sleeve A, provided with the screw d, substantially as and for the purposes set forth.

4. The combination, with the stock B, of the sleeve A, handle C, and the hub D, the handle carrying the blade e, and the sleeve the screw ²⁰ d, substantially as and for the purposes set forth.

5. The sleeve A, provided with the screw d and formed with the flange b, in combination with the stock formed with the depressions a' ²⁵ g and channel e', the hub D, formed with the cut-away place a and channel e, the handle C, and the stop h, the handle carrying the blade e, substantially as and for the purposes set forth.

PATRICK RYAN.

H. A. WEST,
C. SEDGWICK.

It is hereby certified that in Letters Patent No. 254,703, granted March 7, 1882, upon the application of Patrick Ryan, of New York, N. Y., for an improvement in "Billiard-Cue Cutters," the name of the assignee and grantee, wherever it appears in said Letters Patent, and the printed specification attached to and forming a part thereof, was erroneously written and printed "The J. M. Brunswick & Blake Company" instead of "The J. M. Brunswick & Balke Company;" that the correct name is "The J. M. Brunswick & Balke Company;" that the proper corrections have been made in said Letters Patent to make it conform to the files and records pertaining to the case in the Patent Office.

Signed, countersigned and sealed this 14th day of March, A. D. 1882.

[SEAL.]

A. BELL,

Acting Secretary of the Interior.
